TEXTILE PRINTING ROLL

Frank Bromley, Swarthmore, Pa., assignor to
 Joseph Bancroft & Sons Co., Wilmington,
 Del., a corporation of Delaware

Application December 23, 1948, Serial No. 67,038

1 Claim. (Cl. 101—375)

1

This invention relates to textile printing rolls, and its nature, objects and advantages will be best understood from the following:

In textile printing, the web of fabric to be printed is passed around a very large "printing cylinder," and between it and the printing rolls, the number of which varies with the number of colors in the pattern. The large cylinder usually has a suitable covering and is also provided with an endless blanket and sometimes with a web of fabric for blotting, the web of fabric being between the blanket and the printing rolls or between the blotting fabric if employed and the rolls.

The printing rolls are driven and in turn drive the web of fabric to be printed, the blanket and the large printing cylinder, these last being driven driven by virtue of the fact that they are held against the web, blanket and cylinder under pressure.

The conventional printing rolls are either made wholly of copper or a copper sleeve mounted on a steel core or heads, then on a steel mandrel. The patterns are etched on the copper. In either construction, a large amount of copper is required and the weight of the printing rolls is very heavy. Also, because of the great weight of the printing rolls, the power requirements are correspondingly increased. The investment represented by the copper is very large.

The primary object of the invention is to provide an effective printing roll of simple and light construction which will stand up in service, greatly reduce the investment in copper required and which, by reason of its relative lightness, reduces power consumption.

How the foregoing, together with such other objects and advantages as may hereinafter appear or are incident to the invention are realized, is illustrated in the accompanying drawings, wherein—

Fig. 1 is a partial side elevation and longitudinal section through a printing roll embodying my invention;

Fig. 2 is an enlarged fragmentary view partially in section.

Referring now to Fig. 1, it will be seen that my improved roll comprises a mandrel indicated as a whole by the reference character A. This mandrel is composed of an aluminum alloy having good tensile strength such as about 75,000 lbs. or more. The central portion 7 of the mandrel is of relatively large diameter, and it has a slight taper from one end toward the other. The end portions of the mandrel are turned down

2 to provide the shaft portions or journals 8—8 and the still smaller diametered portions 9—9.

The mandrel carries a copper sleeve 10 which is interiorly tapered so that it may be driven onto the central portion 7. The central portion 7 has a keyway 11 and the sleeve 10 has a similar keyway, the sleeve being located by means of a key so that when the mandrel is driven by the source of power (motor or engine) the sleeve will be also driven as a unit.

The conventional procedure when installing the rolls in the printing machine is to pass rope slings around both ends of the mandrel. The roll is then lifted by means of the slings which operate through overhead block and falls. The ends of the mandrels are 9—9. The slots 12—12 are provided so that a tool may be inserted in them to prevent the slings from slipping off the mandrel when the roll is being lifted into the printing machine. Through the use of suitable slots 12—12 these may be utilized in assisting to properly align and adjust the position of the respective printing rolls so as to correctly register the desired pattern.

The journals 8—8 are coated with a suitable bearing metal such as stainless steel, steel or the like, as indicated at 13, to provide them with a suitable bearing surface. (The bearings for the journal are not shown). The stainless steel coatings are desirably $\frac{1}{16}$ " thick. They are provided by spraying the journals 8 with stainless steel, for which purpose the surface of the journals 8 may be roughened or knurled in order to secure a good bond for the sprayed metal. Instead of knurling, a bonding or soldering material may be first applied to the surface of the journal and then the stainless steel sprayed thereon. In either fashion, a firm bond is secured between the journals and the coating. The coating is applied by a spray gun to a greater depth than $\frac{1}{16}$ " and the excess metal is turned off.

Instead of spraying the stainless steel on the aluminum mandrel to form a bearing surface, it is also practical to "sweat on" a steel sleeve over the aluminum shaft, the steel forming the bearing surface.

In the drawings, the wall thickness of the copper sleeve is 1" and the overall diameter of the journals and their coating is $2\frac{1}{8}$ ". From these dimensions the size of the remaining parts can be readily determined. It will be understood, however, that printing rolls vary in diameter but in all cases, according to my invention, 50 the central portion 7 of the mandrel is relatively

large in diameter as compared to the wall thickness of the copper mandrel.

By reason of the construction described, the printing roll is relatively very light as compared to the customary printing rolls in use these many years, but is nevertheless effective and has long life.

In addition to the advantages secured because of a reduction in weight, the construction described possesses several quite unexpected advantages, among which may be mentioned the following:

For reasons not entirely clear to me, a printing roll constructed in accordance with the present invention does not "run hot" in operation. With conventional printing rolls, the temperature of the roll sometimes increases to a point at which one cannot bear to touch it. This is a serious disadvantage, because the printing ink dries out almost instantaneously on an overheated roll, and transfer of the ink to the web being printed is therefore interfered with. This is especially true where printing pastes are used which contain thermosetting resins. The temperature of conventional printing rolls sometimes rises to such a point as to polymerize the thermosetting resin in the ink, under which conditions the printer must be shut down, the roll must be removed, and the hardened ink must be cleaned out of the intaglio engravings on the surface of the roll.

Another advantage inherent in printing rolls fabricated in accordance with the present disclosure is that the rate of temperature rise at the bearings is reduced. This makes for greatly extended bearing life, and reduces the costs of lubrication.

Another advantage attainable by the invention is that, because the structure of the roll is relatively much lighter in weight per unit of volume than in conventional printing rolls, it is possible to increase the diameter of the printing roll beyond what is presently regarded as a practical upper limit on printing roll diameter. That limit is determined to a large extent by the physical capacity of the bearing structure to sustain, first, the weight of the roll, and second, the load imposed when pressure is applied to force the roll into close contact with the web being printed. With rolls of the construction described, substantial increase in diameter is possible without exceeding the deadweight limit of the bearings. Furthermore, the increase in weight due to in-

crease in diameter is offset to some extent because the increase in diameter increases the arc of contact with the web, so that less pressure is needed to ensure thorough transfer of the printing paste from the depressions in the roll to the web being printed. Thus the dynamic load on the bearings is reduced. Still further, the greater the diameter of the printing roll, the fewer revolutions it must make per minute in order to print a given yardage at a given rate. Reducing the number of revolutions per minute reduces wear and temperature rise at the bearings.

It has commonly been supposed that the journals of a printing roll should be made of the hardest, toughest, and most resilient metal available, because of the severity of the conditions under which they are used—high static load, high dynamic load, continuous operation, and little or no tolerance for play or whip. It seems most surprising that an aluminum-alloy mandrel having integral journals of the same alloy would be capable of meeting such rigorous demands.

I claim:

25 A textile printing roll consisting of a solid aluminum-alloy mandrel of cylindrical form, said mandrel having a main body portion of substantial diameter tapering slightly from end to end, and having smaller-diameter integral journal portions of the same alloy at each end, and integral stub end portions of the same alloy projecting beyond each journal portion; an annular jacket of stainless steel bonded to each of said journal portions and constituting a bearing surface therefor; and a copper sleeve on the main body portion of said mandrel having an internal taper mating with the external taper of the mandrel, and keyed thereto.
